CURTAIN

Irving Silverstein, New York, N. Y.

Application June 8, 1935, Serial No. 25,577

4 Claims. (Cl. 156—10)

This invention relates to improvements in curtains.

For some time past it has been the custom to form curtains with a single hem along its opposite longitudinal edges as well as at least on one transverse edge. When a curtain of this type is hung, the longitudinal edges become the vertical edges and the transverse edge, the horizontal edge—and due inherently to the texture of the material from which the curtain is constructed combined with the single hem idea certain objections obtain. The curtain will pucker and sag; it is not truly ornate in appearance; and almost invariably requires the addition of weights to produce a quasi-satisfactory draping.

By certain structural changes, I have eliminated these disadvantages.

To the accomplishment of the recited objects and other co-ordinating therewith the preferred embodiment of my invention resides in the construction and arrangement of parts hereinafter described, illustrated in the accompanying drawing and embodied within the scope of the appended claims.

In the drawing, Fig. 1 is an elevation of a window frame showing the adaptation of a pair of curtains constructed in accordance with my invention.

Fig. 2 is a fragmentary elevation of one corner of a curtain illustrating the structural improvements.

Fig. 3 is a vertical section taken along lines 3—3 of Fig. 2, and

Fig. 4 is a transverse section taken along lines 4—4 of Fig. 2.

Referring more particularly to the drawing, 1 designates a window frame over which a pair of curtains 2 and 3 are draped in conventional fashion. Since these curtains are substantially identical a description of one will suffice.

A certain width of the material from which the curtain is made, as rayon or the equivalent, is folded upon itself at 4 along the longitudinal edge and stitched as at 5 to present a double rolled hem. The fabric 6 is then carried along for a suitable distance away from the longitudinal

edge, again folded upon itself as at 7, and stitched at 8 to provide a second double rolled hem.

This construction may be duplicated along each longitudinal edge of a curtain as well as at the base thereof—see Fig. 3 wherein the double rolled hem structures are denoted in a general way by the reference characters 9 and 10, or if preferred, only one longitudinal or side edge and the bottom edge may be so formed.

Each corresponding set of seams may be constructed separately or simultaneously by means of appropriate machinery.

The side and bottom seams reinforce the curtain fabric so that when it is hung it will be devoid of pockers and/or sags. Because of the extra material required to form transverse hems 9 and 10 sufficient weight is present to obviate the necessity of using curtain-weights. The curtain hangs in smooth graceful folds and retains its cleanly tailored and neat appearance even after laundering or dry cleaning.

In its broader aspects my invention comprises not only the various means shown and described but equivalent means for performing the recited functions. It is desired to reserve the right to effect such changes and modifications as may fairly come within the scope of the appended claims.

I claim:

1. A curtain having a marginal edge folded upon itself along two spaced lines, the folded portions being stitched down at each line.

2. A curtain having one of its side marginal edges and its bottom marginal edge each folded upon itself along two separate spaced lines, the folded portions being stitched down at each line.

3. A curtain having a marginal edge folded on itself, the outer extreme edge and the inner extreme edge of the marginal fold being in turn folded upon themselves along two spaced lines and stitched down at each line.

4. A curtain having a marginal edge folded on itself, the outer extreme edge and the inner extreme edge of the marginal fold having a double-rolled hem therealong.

IRVING SILVERSTEIN.
